J. F. Peabody.

UNITED STATES PATENT OFFICE.

JOHN F. PEABODY, OF SALEM, MASSACHUSETTS.

CHAIR FOR RAILWAYS.

Specification of Letters Patent No. 24,234, dated May 31, 1859.

To all whom it may concern:

Be it known that I, JOHN F. PEABODY, of Salem, in the county of Essex and State of Massachusetts, have invented an Improvement in Chairs for Railways; and I do hereby declare that the same is fully described and represented in the following specification and the accompanying drawings, of which—

10 Figure 1 denotes a longitudinal section of a railway chair and its two bearing rails with my improvement applied thereto. Fig. 2 is a top view of the same; Fig. 3, a transverse section, and Fig. 4, a horizontal section taken so as to show the recess of the chair bed.

15 The nature of my invention consists in an arrangement and application of certain bearings to the base plate of a railway chair, provided with an elastic rubber bearing or 20 its equivalent and a metallic cap piece.

The best mode of carrying out my invention as now known to me I will now proceed to explain.

25 In the drawings, A, and B, represent the rails, while C, denotes their supporting chair. Within the base part *a*, of the said chair a deep recess *D*, is made, the same being formed therein so as to leave bearings 30 *b*, *b*, at each end of it and projecting above its bottom as shown in Fig 1. Within this recess an elastic sheet or plate *E*, of vulcanized rubber, felt, or other suitable material is placed and on the same there is arranged 35 a metallic cap plate *F*, formed to fit the recess and to play easily in a vertical direction therein. This cap plate should extend above the upper surfaces of the bearings *b*, *b*, a distance equal to that to which the elastic 40 rubber bearing *E*, may be safely compressed without injury to its elastic property in order that when the rails may be pressed downward with sufficient force by a weight bearing thereon, they may be caused to descend and bear upon the bearings, *b*, *b*. By 45 applying the elastic bearing within a recess encompassing it around its edges, and being of corresponding size with it or thereabout, it will be prevented from being extended 50 longitudinally and so compressed at its middle as not only to be broken apart, but to

have its elasticity destroyed or materially reduced.

My invention may be said to be an improvement on that which constitutes the 55 subject of the United States Patent No. 15,036, in which the elastic bearing and its cover plate extend the whole length of the chair and are not inserted in a recess or provided with rail bearings independent of the 60 cap plate and extending upward from the base of the chair.

It has been found in practice that when the said bearing and its cover plate are not placed between the rail bearings or in a recess formed in the bed of the chair the elastic bearing will be soon compressed and injured and frequently is found to be torn apart directly under the joint of the rails. My improvement completely obviates this 70 difficulty, for after the elastic bearing, by a load acting on the rails, may have been compressed to the limit beyond which it would be unsafe to go, its further compression will be impossible, by the rails being pressed 75 down upon the bearings *b*, *b*. Thus it will be seen that the said bearings operate as a means of preventing a too great compression of the elastic bearing or one calculated to impair its elasticity or otherwise materially injure it. The intention of the elastic bearing is to prevent the ends of the rails at the joint from being broken down or spread outward. It is advantageous also in other respects so long as its elasticity is not destroyed. It becomes, therefore, of great importance to maintain the elastic power intact, and that it should be sufficient to prevent as far as possible the injurious effects 85 of the downward pressure of the wheels or 90 that of concussion due to percussion on the rails.

When the elastic bearing and its cap plate are placed in a corresponding recess formed in the bed plate and inclosing the 95 entire outer edges of both the elastic bearing is better supported and protected than in any other way of applying it. It may be otherwise applied, however, so long as the rail bearers are arranged with respect to it 100 and the cap plate substantially as specified.

I do not claim covering the india rubber

or elastic bearing with a metallic cap so constructed and applied to the chair as to be free to vibrate or play up and down in a vertical direction as such is the subject of 5 the patent hereinbefore mentioned, but

What I do claim is—

My improvement thereon or the arrangement and application of rail bearers b , b , with respect to the elastic bearing E , its cap 10 plate F , the base plate a , and under the rails

A, B, of the railway chair substantially as described, and particularly with the elastic bearing and cap plate arranged and protected by a recess essentially as explained.

In testimony whereof I have hereunto set 15 my signature.

J. F. PEABODY.
